Application May 12, 1952, Serial No. 287,440

6 Claims. (Cl. 343—225)

This invention relates to circuit arrangements for use in connection with signal-controlled supervisory systems.

The invention is particularly adapted for use in connection with the supervision from remote and/or mobile positions of the conditions of agencies which may require switching operations to respond to a change in a condition at the remote point or points.

It is known to provide at one or more remote points a control signal such, for example, as a radio-frequency carrier wave, some variable characteristic of which is reproduced in amplified form at a terminal station, the variation being used as a control agency to actuate some mechanism. Many of these prior art systems suffer from the disadvantage that they provide at their final output terminals only a low-level of control energy so that extensive use of relay boosters is necessary before any substantial level of control power can be made available.

Such arrangements of the prior art also tend to provide very unsatisfactory service in the presence of transient phenomena and where the control signal fails for unplanned reasons no adequate means is provided for suitably indicating non-operation of the control as distinct from some supervisory intelligence of a predetermined code.

It is an object of the present invention to provide a wave-signal-actuated supervisory switching system or arrangement wherein the above mentioned deficiencies are overcome.

It is a further object of the invention to provide a system of the type indicated wherein the switching agency is more firmly locked up when the control signal is accompanied by noise than it is when the noise is absent.

Another object is to provide a system of the kind indicated wherein a minimum number of conventional components is used to provide power switching of the controlled agency, this object being achieved by the electronic triggering of a power storage device of the "bucket" type.

It will be apparent to those skilled in the art that these and auxiliary objects of the invention are achieved in accordance with the teachings of the invention by the example of construction to be described, and by similar constructions which lie within the ambit of the appended claims.

The invention in its broad aspect, therefore, comprises a signal-controlled supervisory circuit arrangement including receiver means tuned to a desired supervisory wave-signal, a local source of oscillations of a frequency different from that of the said supervisory signal, amplifier means for increasing the levels of both the local oscillations and the said signal in a predetermined ratio, an electron discharge valve arranged to operate as a switch, means for applying voltages related to the said amplified oscillation and the said signal to provide control voltages, means for applying the said voltages to a control electrode of the said electron discharge valve to condition its operation, means for determining the gain of the said amplifier in accordance with a condition of

2

at least one of the amplified signals, and means for adapting the said electron discharge valve to switch the energy contained in a power storage device in order to supervise a specified agency.

5 In an example of construction which will be later described in full detail, the invention comprises a remote control supervisory circuit arrangement including a remotely positioned intelligence-controlled wave-signal transmitter, means for applying the transmitted wave to the input of a receiver tuned to the carrier frequency of the said transmitted wave, a twin-band amplifier associated therewith and including a plurality of inductively-coupled electron discharge valve networks, a control frequency oscillation generator coupled to an input portion of the said amplifier, a heterodyne frequency generator coupled also to an input portion of the said amplifier, an output wave-separating network selectively coupled to the output of the said twin-band amplifier, means for selectively rectifying and integrating the respective outputs of the said separator network, means for applying the resultant unidirectional voltages as bias to control the space-current of an electron discharge valve adjusted to function as a switch, means including a grid-controlled electron discharge valve coupled to the said heterodyne frequency generator to provide an additional control signal dependent upon a condition of said generator for controlling the gain of said amplifier, and means for adapting the said electron discharge valve switching device to control the energy stored in a power storage agency, for the purpose specified.

The above mentioned example of construction will now be described in terms of a preferred embodiment and with reference to the accompanying drawings wherein:

Fig. 1 depicts a preferred form of mobile remote supervisory signal transmitter;

Fig. 2-A depicts one part of a complete terminal-installation circuit diagram comprising a supervisory power-switching arrangement in accordance with the teachings of the invention; and

Fig. 2-B depicts the remaining part of the said diagram, and A and B figures being taken together.

The specification is addressed to those skilled in the art, and therefore the accompanying drawings will be readily understood by those familiar with the operation of electronic discharge devices, although certain well-known details shown therein may not be intimately dealt with in the specification.

Referring now to Figure 1, the remote signal source may be of the portable type employing "miniaturized" components including triode T1 coupled as an oscillator to provide a master-signal at, say, 50 megacycles per second. T2 and T3 wired as shown provide a buffer-amplifier-tank circuit which is loaded by antenna screen A1 and antenna tuning capacitor C1. The antenna radiating element may conveniently take the form of a woven wire tube which contains, within its interior, leads from a battery power-pack. This assembly may be constructed in two parts joined by the antenna-screen/cable A1 and may be readily disposed about the person of a supervising operative.

The transmitter may be provided with a keying device (not shown) whereby suitable variations may be applied to the signal according to a predetermined code.

The signal from the transmitter is radiated in a predetermined manner and is intercepted by any antenna within its range, such as aerial A2 (Fig. 2-A).

Figs. 2-A and 2-B taken together embrace the whole of a preferred supervisory terminal switching arrangement.

70 Electron discharge valves V1 and V2 together with their associated LC and service networks comprise a twin-band receiver-amplifier which by suitable adjustment of

the LC values in the reactive networks is made capable of simultaneously amplifying the received supervisory signal and the first local source of oscillations. It will be noted that the respective LC networks are arranged in series, in each case, with the respective grid-control elements, and this will be referred to again later.

Since **V2** acts as an amplifier and mixer it heterodynes the supervisory incoming signal, amplifies it in terms of its conversion gain and passes a predetermined intermediate signal by way of the appropriate LC network to **V3** plus the fundamental first local oscillation by way of its discreet LC networks.

Electron discharge device **V4** couples the output of this amplifier to a pair of electron discharge devices **V5** and **V6** whose input LC networks are so connected that one of the twin-band signals, the H. F. intermediate frequency, appears on the grids of **V5** and **V6** in phase opposition while the other of the twin-band signals, the lower high frequency first local source of oscillations, appears cophasally upon the said grids, and the output networks of **V5** and **V6** are arranged to preserve a similar phase relationship so that the output signals, if of predetermined similarity in amplitude at the input of the system, will present a ratio of peak-voltage level which will be a ratio of the push-pull vs. cophasal gain characteristic of the respective LC networks.

The respective signals, now in a set ratio to one another, are split off into two suitably tuned rectifier networks including, respectively, rectifiers **D3** and **D4**, and the outputs of these devices are passed through respective long time-constant integrating networks which provide two predetermined unidirectional output voltages. These will be referred to again later.

Electron discharge valve **V9** and its associated networks comprise a first local control frequency generator which is coupled to an injector grid of a multielement valve **V10** of the oscillator-mixer type, and the output of this arrangement is in turn inductively and capacitively coupled by stray field effects to the input stage including **V1** of the twin-band amplifier. Signals from **V9** will now appear through **V10** upon the control grid of **V1**.

If the frequency of the remote control signal is of the order of 50 megacycles, the separate first local control frequency should be preferably of the order of 200 kilocycles. If an oscillator section of **V10** is arranged to operate at 58 megacycles, a heterodyne frequency of the order of 8 megacycles will appear at the grids of **V2**—**V6** whenever a signal from the transmitter is intercepted by **A2**, and the LC networks of this channel of the twin-band amplifier should be tuned accordingly. The other channel of the twin-band wave translation networks is adjusted to respond to the separate 200 kilocycle control frequency.

It will be now observed that the upper set of LC networks in the twin-band amplifier associated with **V2** through **V3**, **V4**, **V5** and **V6** to **D4** and **D3**, are band-pass for the 8 megacycle signal and high-pass for the 200 kilocycle signal, while the lower set of LC networks is band-pass for the 200 kc. signal and low-pass against the 8 megacycle signal. Thus the combined networks associated with valves **V3**—**V6** are able to translate efficiently and simultaneously two signals widely separated in frequency, one of them being the local signal from **V9** and the other a signal dependent upon conditions at the remote supervisory point.

The rectified and smoothed control voltages from these two signals appear at points **K** and **S** respectively (Fig. 2-B).

Control voltage **K** stemming from oscillator **V9** is constantly available as soon as the equipment is set in operation and unless removed will block-off electron discharge device **V7**.

It will be obvious to those skilled in the art that having regard to the specific disclosure made in the drawing ad-

justment of control voltages on **V7** and **V2** in respect to the developed control voltages from **V9** and the antenna can be so modified as to reverse operation characteristics of the controlled supervisory point.

5 Control signal **S** stems from the 50 megacycle remote control signal and is picked off the ratio network at the push-pull level. Signal **S** will normally be much higher in level than signal **K** if both start in at the same order of magnitude. Control signal **S**, when present, is fed over 10 isolating resistor **R1** to the injector grid of **V10**, and together with the signal from **V9** already present on this grid tends to bias off the cathode stream of **V10** at this grid-level. The oscillator section of **V10** is, however, operating at different points in the cathode-stream and 15 the signal from **V10** oscillator will not be greatly affected. Thus when signal **S** appears at **V10** signals from **V9** are cut off from **V1**, signal **K** disappears, and **V7** is unblocked.

The carrier as "seen" by the antenna **A2** will in most cases be quite low in amplitude and it is a well-known characteristic of wide-band high gain superheterodyne amplifiers that the ENSI and other unwanted parasitics are higher at low signal levels than at zero signal. Noise, therefore, when it accompanies the external control signal, tends to add to the magnitude of signal **S** 20 but will normally be of insufficient magnitude to cause interruption of the **V9** oscillation (signal **K**) when there is no external control signal present. It is evident that the present circuit arrangement is virtually noise-proof at one position of control and completely noise-proof at the other position.

All arrangements of this kind are subject to possible failure of some valve or component from time to time. It is evident in the present case that any failure of signal **S** alone will throw switching valve **V7** into the quiescent state. If **V10** were to fail as an oscillator the external control signal would not pass through the amplifier and **S** would fail. If, however, **V9** were to fail at the same time, the signal at **K** would also fail and **V7** would be biased into the active state and "freeze" in that condition. If **V9**, only, failed and **S** remained steady **V7** would again "freeze" in active state. If any of the valves in the amplifier failed, both **S** and **K** would disappear and again **V7** would "freeze" in the active state. **V7** being preferably a "power" valve its failure would in most cases be due to gassy breakdown which would cause **V7** to defy its bias controls and, again, "freeze" in the active state. Therefore, only one likely cause of system failure would throw **V7** over into a state of frozen quiescence, namely, a failure of **V10** as an oscillator. **V8** has been introduced into the system to provide, in association with a detector-integrator network, means for blocking the amplifier and thus causing both **S** and **K** to fail if **V10** fails. Oscillation from **V10** is coupled to a control grid of **V8** which is connected as an amplifier tuned to the second source of oscillations. It supplies at "B" (Fig. 2-B) one of two bias voltages which together provide **V2** with its grid base. Failure of **V10** wipes out one component of the grid base and so depresses the gain of **V2** to a point where both **S** and **K** fail and cause 40 **V7** to now freeze in the active rather than in the quiescent state.

Now, any likely cause of system failure will freeze **V7** in the active state so that failures in the terminal equipment are easy to distinguish from failure at the 45 remote point (which would freeze **V7** in the other state).

Although it has been stated that **V7** is preferably a "power" valve it is not desirable, in the interests of economy, to employ any large high gain electronic devices in equipment of this type. However, in the field of utility terminals **P1**, **P2**, **P3** (Fig. 2-B) may be called upon to handle kilowatts of power necessitating large heavy contacts which place a heavy demand upon the magnetic circuit associated with **L2**. A low powered **V7** would not readily energize such a system, and the adoption of 50 a control relay to power such a contactor from the sup-

ply mains would involve considerable reactive surge effects thereby giving rise to maintenance problems from contact sparking and necessitating the addition of costly anti-radio-interference equipment.

This problem has been solved in an ingenious manner by adapting the space current of V7 to control the discharge cycle of a "bucket" storage capacitor, CB of Fig. 2-B, which is charged at a relatively slow rate through limiting resistor R2 from the apparatus power-pack.

When V7 is blocked relay magnet L1 is not fluxed and when S1 and S2 are closed L2 (which may be a low impedance high energy magnet to actuate S3) is fluxed by the heavy current discharge from CB. When S1 is opened, the bucket capacitor is released from its load, L2 releases and CB is recharged slowly through R2.

The ratio of impedance L2 and resistance R2, expressed in ohms, must of course, be kept high, the higher this ratio is maintained the greater is the power that can be stored in CB for a given rate of cycling.

It is evident that the relay magnets and contacts can be arranged to be normally open or normally closed in a number of combinations which will readily occur to those skilled in the art; these can be selected to suit a given application in the field of utility.

The exemplifications contained in the foregoing paragraphs are not to be taken as limiting the scope of the invention to the particular forms discussed. The teachings of the invention are to be construed in accordance with the scope of the appended claims.

What I claim is:

1. A signal-controlled supervisory circuit arrangement including receiver means tuned to a desired supervisory high frequency wave-signal, a local source of high frequency oscillations of a frequency different to that of the said supervisory signal, amplifier means for separately increasing the levels of both the local oscillations and the said signal in a predetermined ratio, an electron discharge valve arranged to operate as a switch detector, means for deriving voltages from the said amplified oscillation and the said signal to provide control voltages, means for applying at least one of said voltages to a control electrode of the said electron discharge valve to condition its operation, means for determining the gain of the said amplifier in accordance with the magnitude of at least one of the amplified signals and means for adapting the said electron discharge valve to switch the energy contained in a power storage device in response to a change in a said one control voltage.

2. A signal controlled supervisory circuit arrangement comprising receiver means tuned to a desired high frequency supervisory signal, a local high frequency source of oscillations of a frequency greatly different from that of the said supervisory signal two band, amplifier means capable of simultaneously increasing the levels of both the local oscillations and the said signal independently in a predetermined basic ratio, an electron discharge valve arranged to operate as a switch, means capable of separately acquiring voltages respectively related to the said amplified oscillation and the said signal to provide two unidirectional control voltages, means for applying at least one of the said voltages to a control electrode of the said electron discharge valve to set in a first operative condition, means for determining the gain of the said amplifier in accordance with the magnitude of at least one of the amplified signals and means responsive to the said control voltages for adapting the said electron discharge valve to switch to a second condition when a change occurs in a characteristic of said local oscillation.

3. A signal controlled supervisory circuit arrangement comprising receiver means tuned to a desired high frequency supervisory signal, a first high frequency local source of signal control oscillations having a frequency greatly less than that of the said supervisory signal, a second local source of oscillations of a frequency higher

than that of the said supervisory signal, amplifier means capable of simultaneously increasing the levels of the first local oscillation and a signal representing a difference between the second locally generated oscillation and the

5 said supervisory signal in a predetermined basic ratio, an electron discharge valve arranged to operate as a switch, means for obtaining control voltages related to the magnitude of said first local oscillation, and said difference-signal, means for applying the said control voltages as bias to define a first condition of the said electron discharge valve, means responsive to a control voltage related to a condition of the said second local oscillation for controlling the gain of the amplifier in accordance with a specified characteristic of one said difference signal, and means responsive to a change in a characteristic 10 of said second local source of oscillations for adapting the said electron discharge valve to switch to a second condition.

4. A signal controlled supervisory circuit arrangement 15 comprising receiver means tuned to a desired high frequency supervisory signal, a first local source of high frequency signal control oscillations having a frequency greatly less than that of said supervisory signal, a second local source of oscillations having a frequency different

20 by a predetermined amount from that of the said supervisory signal, amplifier means capable of simultaneously increasing in a predetermined ratio the levels of the first local control signal oscillation and a signal representative of a difference between the frequency of the second locally generated oscillation and that of the said supervisory signal, means including rectifiers and integrating networks for obtaining two smooth unidirectional control voltages each related in amplitude to an amplitude characteristic of the first said amplified local oscillation

25 and of said amplified difference-signal, an electron discharge valve network having two stable conditions and connected to operate as a switch, means for applying the control unidirectional voltage representative of said first local signal control oscillation as bias to a control electrode of said electron discharge valve network to establish therein one of said stable conditions, means for selectively applying the other said control unidirectional voltage to an agency associated with the first source of local signal control oscillations whereby the latter are prevented

30 from generating the corresponding control voltage when the said other control voltage is present thereby to change the said electron discharge valve network over to its second stable condition bias, means responsive to the absence of a predetermined amplitude characteristic of the second

35 local source of oscillations for blocking the amplifier thereby removing both control voltages and setting the electron discharge valve network in its second stable condition, a power storage capacitor, resistive connections for charging said capacitor from a source of unidirectional

40 electric energy, electromagnetic switching means for connecting the said capacitor to a relatively low impedance work circuit, means for utilizing the alternate stable states of the electron discharge valve network to determine the energy condition of the said electromagnetic switching means, and means for utilizing the low impedance work circuit to control the condition of a principal supervising agency.

5. A remote control supervisory circuit arrangement 45 comprising a remotely positioned intelligence-controlled signal transmitter of the miniaturized portable type where-in a portion of the connecting means between two parts of the apparatus includes means in the form of a flexible metallic pipe connected to radiate a supervisory electromagnetic wave signal, receiver means responsive to said

50 wave signal, a first local source of signal control oscillations having a frequency greatly less than that of said supervisory signal, a second local source of oscillations having a frequency different by a predetermined amount

55 from that of the said supervisory signal, amplifier means capable of simultaneously increasing in a predetermined

60 local source of oscillations for blocking the amplifier thereby removing both control voltages and setting the electron discharge valve network in its second stable condition, a power storage capacitor, resistive connections for charging said capacitor from a source of unidirectional

65 electric energy, electromagnetic switching means for connecting the said capacitor to a relatively low impedance work circuit, means for utilizing the alternate stable states of the electron discharge valve network to determine the energy condition of the said electromagnetic switching means, and means for utilizing the low impedance work circuit to control the condition of a principal supervising agency.

70 75 7. A signal controlled supervisory circuit arrangement comprising receiver means tuned to a desired high frequency supervisory signal, a first high frequency local source of signal control oscillations having a frequency greatly less than that of the said supervisory signal, a second local source of oscillations of a frequency higher

ratio the levels of the first local control signal oscillation and a signal representative of a difference between the frequency of the second locally generated oscillation and that of the said supervisory signal, means including rectifiers and integrating networks for obtaining smooth unidirectional control voltages each related in amplitude to a respective characteristic of the first said amplified local oscillation and of said amplified difference-signal, an electron discharge valve network having two stable conditions and arranged to operate as a switch, means for applying the control voltage representative of said first local signal control oscillation to a control electrode of said electron discharge valve network to establish therein one of said stable conditions, means for applying the other said control voltage to an agency associated with the first source of local signal control oscillations whereby the latter are prevented from reaching the amplifier to generate the corresponding control voltage, thereby to change the said electron discharge valve network over to its second stable condition, means responsive to the absence of a predetermined characteristic of the second local source of oscillations for blocking the amplifier thereby removing both control voltages and setting the electron discharge valve network in its second stable condition, a power storage capacitor, resistive connections for charging said capacitor from a source of unidirectional electric energy, electromagnetic switching means for connecting the said capacitor to a relatively low impedance work circuit, means for utilizing the alternate stable states of the electron discharge valve network to determine the energy condition of the said electromagnetic switching means and means for utilizing the low impedance work-circuit to control the condition of a principal supervising agency.

6. A signal controlled supervisory circuit arrangement comprising a receiver means tuned to a desired high frequency supervisory signal, a first local source of high frequency control-signal oscillations having a frequency greatly less than that of the said supervisory signal, a second local source of oscillations having a frequency different from that of the said supervisory signal and coupled thereto to provide a difference signal, a twin-band
